Application June 21, 1951, Serial No. 232,752

8 Claims. (Cl. 250—36)

This invention relates to oscillators for generating high frequency electrical currents. More particularly, it relates to such oscillators which are tunable so that they can be adjusted to operate at any frequency within a relatively wide frequency range.

The tuned circuits of such high frequency generators are usually formed by resonant chambers or cavities associated with one or more of the tube elements. For example, one resonant cavity may be coupled to the tube plate and another resonant cavity may be coupled to the control grid or cathode of the tube, suitable feedback to the control element being provided to produce the desired oscillation.

The resonant frequency of such cavities can be varied by changing the physical dimensions of the cavities. Thus, one wall of the cavity is sometimes formed by a movable plunger having flexible contact fingers. By moving the plunger, the size of the cavity and its resonant frequency is varied. At very high frequencies, for example of the order of three thousand million cycles per second, it is difficult to maintain efficient operation at all frequencies within the tuning range.

Moreover, it is usually necessary to provide two such tunable cavities if the frequency of oscillation is to be varied over a substantial range of frequencies. This makes it tedious to change the frequency of the oscillator, as it is difficult for the operator to make the two adjustments in such manner as to secure optimum operation at the desired frequency. It is not easy to gang the two tuning adjustments because the extent of movement required to produce a given change in frequency is usually different for the two tuning elements, and the likelihood of spurious modes of oscillation further complicates the problem. Such plungers also cause trouble when the contacting fingers become dirty or lose their resiliency so that good contact is not maintained.

The present invention overcomes many of these and other disadvantages and is described as embodied in a compact, wide-range, single control, tunable oscillator that is simple in construction and efficient in operation. In a preferred embodiment of the invention, a folded, fixed-tuned, broad-band cathode cavity is provided, and a single adjustment alters the characteristics of a simple coaxial plate cavity to vary the frequency throughout a relatively wide range.

These and other aspects, objects, and advantages of the invention will be in part pointed out in and in part apparent from the following description of the preferred embodiment of the invention considered in conjunction with the accompanying drawings, in which:

Figure 1 is a perspective view of a cavity type oscillator embodying the invention;

Figure 2 is an exploded perspective view showing certain components of the oscillator of Figure 1; and

Figure 3 is an enlarged longitudinal sectional view of the oscillator shown in the preceding drawings.

The oscillator shown in the drawings is adapted for operation in the 3,000 megacycle region and uses a pencil triode tube, generally indicated at 2, for example, of the A2317 series.

2

The tube 2 is provided with a cylindrical metal portion 4 through which connection is made to its cathode, the connections to the heater being made through two leads 6 and 8.

6 In order to provide the folded back resonant cavity for the cathode, a cylindrical metal sleeve 10, in threaded engagement with an annular metal block 12, is provided with an outwardly extending flange 14 the outer edge of which is secured to the end of an outer sleeve 16 positioned concentrically around, but spaced from, the internal sleeve 10. An intermediate sleeve 18 is interposed between the sleeves 10 and 16 and is supported at one end by the block 12. The opposite end of the sleeve 18 is spaced from the flange 14 to provide a folded cavity

15 having a first cavity portion between the sleeves 10 and 18 that opens adjacent the flange 14 into a second cavity portion between the sleeves 16 and 18. This second cavity portion opens into the annular cavity space between the sleeve 16 and the inner surface of an outer supporting tube 20.

20 The connection to the planar control grid of the tube 2 is made by means of an annular flange 22 surrounding the central portion of the tube. A grid sleeve 24 is secured to the flange 22 by any suitable means, for example, or by a ring 25 that is press-fitted into or is in threaded engagement with the flange 22. This flange 24 extends concentrically within but is spaced from the shell 20.

25 Electrical connection is made with the grid sleeve 24 by a spring contact 26 that presses against the outer surface of the grid sleeve. External connection to the grid sleeve contactor 26 can be made by means of a lead 28 that extends through and is insulated from an outwardly-extending metal shield member 32. The diameter of the lead 28 is increased within the tubular shield 32 to form

30 a condenser 33 that provides a capacity of at least 15 micromicrofarads between the grid lead 28 and the shell 20. This capacitance is important and helps to suppress undesired oscillation modes. In many circuit arrangements, the grid contactor 26 can be connected advantageously directly to the shell 20. These or other arrangements can be used, but it is important that some means be provided so that the impedance between the grid contactor 26 and the shell 20 is low at the frequency of operation.

35 40 A metal sleeve 34, which forms part of the tube 2 and is connected to its anode, is connected to a sleeve 36 that forms the inner conductor of the coaxial plate cavity. This sleeve 36 is provided with contact fingers 37 that engage the tube sleeve 34 and at the opposite end is closed and is connected to an electrical conductor 38 by which connection is made between the external electrical circuits and the anode of the tube 2.

45 The end of the sleeve 36 is maintained at the radio frequency potential of the interior surface of shell 20 by 50 means of a capacitance sleeve 40. This sleeve is provided at one end with an internal annular flange 42 positioned in face to face relationship with an external annular flange 44 on the sleeve 36.

55 The sleeve 40 is maintained in secure electrical contact with the flange 44 and is supported by a number of screws 46 that extend through clearance openings in an insulating supporting block 48 and in the flange 44 into threaded engagement with the flange 42. The capacitance sleeve 40 is spaced from the inner surface 60 of the shell 20 so that the direct plate potential is not applied to the shell 20, but the capacity between the shell 20 and the sleeve 40 is sufficient to maintain the radio frequency potential of the sleeve 40 at the same potential as the interior surface of shell 20. An end cap 50 closes the end of the shell 20 and is maintained in position by screws 52.

65 In order to permit variation in the frequency of the

signal generated by the oscillator, a variable capacitance element, generally indicated at 54, is arranged between the sleeve 36 and the shell 20 and is positioned at a point on the sleeve 36 where there is substantial radio frequency voltage.

A metal plunger 56 is in threaded engagement with the internal surface of a supporting metal tube or sleeve 58 that is secured to the shell 20. The inner end of the plunger 56 is provided with a recessed portion 60 that permits a metal projection 62 on the sleeve 36 to extend within the end of the plunger 56 as the plunger 56 is rotated within the tube 58 so as to move toward the sleeve 36. The change in capacity between the plunger 56 and the projection 62, that is between the sleeve 36 and the shell 20, as the plunger 56 is moved inwardly or outwardly, changes the frequency of operation of the oscillator.

It will be noted that the capacity is predominately between the surfaces of the plunger 56 and the projection 62 that are parallel with the direction of movement of the plunger 56, thus providing a more nearly linear relationship between the frequency and the physical position of the plunger 56 than if the end surface of the plunger 56 were used as one of the capacitive surfaces.

Power is taken from the oscillator by a conventional coupling loop, generally indicated at 64.

With the arrangement described above, the frequency of the signal generated by the oscillator is in the 3,000 megacycle region can be varied as much as 200 to 400 megacycles by adjusting the plunger 56 and without making any other adjustments. Satisfactory power output is maintained throughout the operating range.

It will be noted that the characteristics of the cathode circuit remain unchanged throughout the tuning range. The disclosed folded cavity has been found to have the desired characteristics for permitting this unusually wide tuning range.

It will be noted also that the free end of the grid sleeve 24 is directed toward the plate cavity. In practice, this permits a substantially greater tuning range than if the sleeve is directed toward the cathode cavity.

The slots in the sleeve 24 are for the purpose of preventing circulating currents in the grid sleeve and, therefore, increase the efficiency of the oscillator. The particular dimensions of the cavities will be selected so that under the existing loading conditions the desired frequency of operation is attained. With the illustrated arrangement, good results have been obtained when the effective length of the cathode cavity is 1.25 wavelengths and the plate cavity is 0.75 wavelength at the center frequency of operation.

From the foregoing, it will be apparent that we have provided a highly useful, high frequency oscillator well adapted to attain the ends and objects heretofore set forth. It will be apparent to those skilled in this field that various changes and modifications may be made in the illustrated embodiment to adapt the invention to particular uses without departing from the scope of the invention as set forth in the following claims.

What is claimed is:

1. A high frequency tunable oscillator adapted to utilize a tube having a cathode, a control grid, and an anode comprising a first folded cavity type resonant circuit, means for conductively connecting said first cavity to the cathode of said tube, a second coaxial type cavity having an inner and outer conductor, means for coupling said second cavity to the anode of said tube, a first movable conductive capacitive tuning element mounted on one of said conductors, and a fixed capacitive element mounted on the other of said conductors, one of said capacitive elements having a recess therein adapted to receive a portion of the other capacitive element, a metallic shell forming part of each of said cavities, a sleeve member positioned concentrically within and closely spaced from said shell, said sleeve member substantially dividing said first and second cavities from each other, and means for connecting said sleeve to said grid.

2. A high frequency tunable oscillator adapted to utilize a tube having a cathode, a control grid, and an an-

ode comprising a first folded back cavity type resonant circuit, means conductively connecting said first cavity resonant circuit to the cathode of said tube, a second coaxial type cavity circuit having an inner and outer conductor, means for coupling said second cavity circuit to the anode of said tube, and first and second conductive capacitive tuning elements mounted, respectively, on said conductors, said capacitive elements being relatively movable transversely of said second cavity in spaced overlapping relationship.

3. A high frequency tunable oscillator adapted to utilize a pencil-type tube having a cathode, a control grid, and an anode comprising a first folded cavity type resonant circuit, means for coupling said first cavity to the cathode of said tube, a second coaxial type cavity circuit having an inner and outer conductor, means for coupling said second cavity to the anode of said tube, a first movable conductive capacitive tuning element mounted on one of said conductors, and a fixed capacitive element mounted on the other of said conductors, one of said capacitive elements having a recess therein adapted to receive a portion of the other capacitive element, a metallic shell forming part of each of said cavities, a sleeve member positioned concentrically within and closely spaced from said shell, said sleeve member substantially dividing said first and second cavities from each other, and means for connecting said sleeve to said grid.

4. A high frequency tunable oscillator adapted to utilize a tube having a cathode, a control grid, and an anode comprising a first folded cavity type resonant circuit, means for physically connecting said first cavity directly to the cathode of said tube, a second coaxial type cavity having an inner and outer conductor, means for coupling said second cavity to the anode of said tube, and a variable capacitor mounted on said outer conductor of said second cavity and having a conductive element movably mounted relative to said inner conductor for varying the frequency of operation.

5. A high frequency tunable oscillator adapted to utilize a tube having a cathode, a control grid, and an anode comprising a first folded cavity type resonant circuit, said first cavity communicating directly with the cathode of said tube, a second coaxial type cavity having an inner and outer conductor, means for coupling said second cavity to the anode of said tube, a conducting member effectively substantially completely separating said folded cavity type resonant circuit from said coaxial type cavity, means for coupling said member to the grid of said tube, and a variable capacitor connected between the inner and outer conductors of said second cavity for varying the frequency of operation.

6. A high frequency tunable oscillator adapted to utilize a tube having a cathode, a control grid, and an anode comprising a first folded cavity type resonant circuit, means defining a passage electromagnetically coupling said first cavity directly to the cathode of said tube, a second coaxial type cavity circuit having an inner and outer conductor, the effective electrical length of said second cavity being equal to approximately six-tenths the effective electrical length of said first cavity, means for coupling said second cavity to the anode of said tube, electrically conductive means effectively substantially completely separating said first and second cavity resonant circuits, and a variable capacitor connected between the inner and outer conductors of said second cavity for varying the frequency of operation.

7. A high frequency tunable oscillator adapted to utilize a tube having a cathode, a control grid, and an anode comprising a first folded cavity type resonant circuit, means for physically directly connecting said first cavity to the cathode of said tube, a second coaxial type cavity circuit having an inner and outer conductor, the effective electrical length of said second cavity being equal to approximately six-tenths the effective electrical

length of said first cavity, means for coupling said second cavity to the anode of said tube, a variable capacitor connected between the inner and outer conductors of said second cavity for varying the frequency of operation, and screw means for adjusting said capacitor. **18** A high frequency tunable oscillator adapted to utilize a tube having a cathode, a control grid, and an anode comprising a folded-back cavity type resonant circuit including an outer cylindrical conductive shell, a first conductive sleeve within said shell defining a first annular cavity portion between said shell and first sleeve, a second conductive sleeve within said first sleeve defining a second annular cavity portion between said first and second sleeves, said second cavity portion communicating near one end with said first cavity portion near one of its ends, and a third conductive sleeve within said second sleeve defining a third annular cavity portion between said second and third sleeves, said third cavity portion communicating near one end with said second cavity portion near the opposite end from that which communicates with said first cavity portion, said third sleeve being coupled to the cathode of said tube, a second coaxial type cavity having an inner conductor and

an outer conductor, means for coupling said second cavity to the anode of said tube, a conducting member substantially dividing said coaxial type cavity from said folded-back cavity type resonant circuit, and first and second conductive capacitive tuning elements mounted, respectively, on said conductors, said capacitive elements being relatively movable transversely of said second coaxial-type cavity in spaced overlapping relationship.
